UNITED STATES PATENT OFFICE.

BUTLER AMES, OF LOWELL, MASSACHUSETTS.

RAZOR.

1,192,367.

Specification of Letters Patent. Patented July 25, 1916.

Application filed July 2, 1915. Serial No. 37,681. REISSUED

To all whom it may concern:

Be it known that I, BUTLER AMES, a citizen of the United States, residing at Lowell, in the county of Middlesex and State of Massachusetts, have invented certain new and useful Improvements in Razors, of which the following is a specification, reference being had therein to the accompanying drawing.

10 My invention relates particularly to means for removably securing a metallic blade of an instrument, say a razor, to its support or handle; and may be said to reside in a suitable structure making use of 15 magnetism in attaining this purpose.

The advantages of such a structure are that it does away with the necessity of using screw connections formerly employed, the parts may be assembled or taken apart with 20 great ease and speed; there are no small parts to be dropped and lost; and the magnetic lines of force, while the blade is in position, flow through it with a beneficial 25 effect of improving the cutting qualities of 2b the blade.

In the drawings illustrating the principle 30 of my invention and the best mode now known to me of embodying the same in operative structure, Figure 1 is an elevation partly in section of a razor embracing my 35 invention; Fig. 2 shows an end view of the same; Fig. 3 is a plan of it; Fig. 4 illustrates an enlarged detail, one pole piece of a magnet provided with coöperating parts for attaining the object of my invention; Fig. 5 is a perspective view showing the manner 40 of assembling or demounting the razor blade and its co-acting members.

A horseshoe magnet 1 of such size as to 45 be conveniently grasped in the hand, has legs 2 which are circular in cross section, say one-quarter of an inch in diameter, and one inch apart. They are made of magnet steel, and then hardened the desired amount, 50 but before they are so hardened, each pole piece of the magnet, in the direction of its length, has a threaded hole provided for the reception of a metallic flat-headed retaining screw 3 later to be described. A ring 4 of 55 soft iron having the same diameter as the legs of the magnet, abuts the end of each leg, while a cross bar 5 of brass or other non-magnetic material provided with safety fingers 5a, is mounted upon, and unites these 60 end portions of the magnet; the under and

upper sides of the safety bar being recessed to receive respectively the rings and the flat-headed screws 3; the tops of the heads being flush with the top surface of the safety bar. Permanently fixed in the longitudinal axis 60 of each screw is a round nosed guide and lock pin 6, which necessitates having spanner holes in the screw head. A thin rectangular double razor blade 7 with two holes registers with the guide and lock pins 65 6; as does a lock cap 8 of soft iron, the cap being narrower and longer than the blade, while the blade is narrower than the safety bar with its protecting fingers 5a. In short, the above apparatus described is a safety 70 razor provided with a magnetically rather than mechanically secured blade.

It will be observed that the magnet, rings, screws, guide pins and bar are for all practical purposes permanently assembled 75 for use and form a unitary structure; while the lock cap and blade are manually separable.

When the parts of the complete magnet are in operative position, the magnetic lines 80 of force flow from one pole of the magnet to the other, that is to say, for example, from the leg, through the ring, screw, guide pin, cap and razor blade, and the guide pin, 85 screw, ring of the leg.

The guide pins rigidly prevent lateral and longitudinal movement of the blade and cap with relation to the legs of the magnet, while the strength of the magnetic field is sufficient to hold the blades in operative 90 position against the safety bar.

If the blade is to be removed, the ends of the cap are grasped between the thumb and first finger, and, against the magnetic attraction the cap may be removed, and then 95 by a similar operation the blade may be disengaged from the guide and lock pins, and the safety bar. To removably secure the blade to the magnet a reversal of the steps would accomplish that end.

Desiring to protect my invention in the broadest manner legally possible, what I claim is:

1. A U-shaped magnet having two adjacent pole pieces; a metallic blade; a bar of 105 non-magnetic material mounted upon the pole pieces said magnet to serve as an abutting surface for said blade; a cap of magnetic material serving with the blade as an armature for the magnet; means to prevent 110

the longitudinal and lateral movements of said blade and said cap in relation to said bar.

2. A magnet having two adjacent, separate, soft iron pole pieces; a bar of non-magnetic material extending across and being recessed to receive said pole pieces; a flat headed screw with spanner holes whereby each pole piece and each end portion of the bar may be secured to their respective leg of the magnet; a pin centrally mounted in the axis of each screw; a metallic blade

with suitable holes for said pin to engage; and a cap of magnetic material also engaged by said pin, and serving as an armature for the magnetic circuit to confine the blade in abutment with the non-magnetic bar. 15

In testimony whereof I hereunto affix my signature in the presence of two witnesses. 20

BUTLER AMES.
